UNITED STATES PATENT OFFICE.

HOWARD M. DUDLEY, OF PHILADELPHIA, PENNSYLVANIA.

FABRIC-TREATING DEVICE.

1,266,110.

Specification of Letters Patent. Patented May 14, 1918.

Application filed June 20, 1917. Serial No. 175,727.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Fabric-Treating Devices, of which the following is a specification.

My invention relates to improvements in fiber treating machines and refers particularly to machines adapted to the dyeing, steaming and crabbing of piece goods.

In the dyeing of goods in the piece, the greatest care must be exercised in order to cause complete penetration of the dyestuff and even shades.

The dyeings of many dyestuffs require an after-treatment with such products as metallic-salts, or oxidizing agents in order to develop the best results. It is also necessary to thoroughly wash the goods at various stages of the operation and to dry them when finished.

As each one of these operations has an effect upon the results, it is essential that all of the treatments be uniform throughout the fiber and that they be readily controlled.

One object of my invention is a device in which the piece goods may be uniformly subjected to a solution of a dye.

Another object of my invention is a device in which thorough penetration of textile fabrics may be effected by either a liquid or steam.

Another object of my invention is a device in which dyed fabrics may be uniformly and thoroughly after-treated with a liquid, air or gas.

Another object of my invention is a device in which the fabrics may be thoroughly dried.

Another object of my invention is a device in which fabrics may be dyed, washed, after-treated and dried in a thorough and uniform manner without handling them.

Another object of my invention is a device in which piece goods may be crabbed, steamed, dyed, after-treated and dried without removal from the device.

Another object of my invention is a means whereby the device may be readily and effec-

tively adjusted to conform with fabrics of different widths.

Other objects of my invention will be evident upon a consideration of my specification and claims.

In the accompanying drawings, which illustrate several modifications of the device of my invention, similar parts are designated by similar numerals.

Figure 1 is a vertical cross-section of one form of my device.

Fig. 2 is a cross-section through the line 2—2 of Fig. 1.

Fig. 3 is an end view of Fig. 1 looking in the direction of the arrow 3.

Fig. 4 is a cross-section through the line 4—4 of Fig. 1.

Fig. 5 is an enlarged broken cross-section showing in detail the means for closing a portion of one of the foraminous plates.

Fig. 6 is a top plan view of the chain covering.

Fig. 7 is a broken vertical cross-section of the chain covering through the line 7—7 of Fig. 6.

Fig. 8 is a cross-section of a modification of the tubular arrangement within the reel.

Fig. 9 is an end view showing a modification of the foraminous plate.

Fig. 10 is a broken cross-section through the line 10—10 of Fig. 9.

Fig. 11 is a broken side view of a modification of the bars of the foraminous plate.

Fig. 12 is an end view of Fig. 11.

The particular form of my device, as illustrated, comprises a dyeing chamber formed by the bottom member 7 and the top member 8, hingedly attached thereto and capable of being held in intimate contact by means of the screw bolts 9, 9. A pipe 10, opening into the top of the dyeing chamber is connected to a system (not shown) whereby the liquid passing from the dyeing chamber may be returned for repassage through said chamber.

Within the dyeing chamber is a reel, around which the cloth to be dyed or treated is wound, comprising the two end flanges 16, 16^A, to which are fixedly attached the two annular foraminous plates 17, 18. The two flanges 16, 16^A extend into the shells 19, 19^A.

of the hollow core of the reel extending outwardly from opposite ends of the dyeing chamber. Fixedly attached to the shell 19^A is a cogged wheel 20, meshing with the worm gear 21 which is fixedly attached to the shaft 22, from which a revoluble movement may be imparted to the shells 19, 19^A and the reel. Extending into the shells 19, 19^A are the pipes 28, 28^A around which the shells 19, 19^A 10 are revoluble. The pipes 28, 28^A are connected to a source of liquid, steam or air supply.

In order to reduce the width of the foraminous plate 18 through which the liquor 15 passes to coincide with the width of the fabric to be treated, the following device is employed. The flanges 16, 16^A carry annular outwardly extended abutting members 40, 40^A, fixedly attached thereto by a 20 series of bolts 41. Surrounding the foraminous plate 18 and abutting thereon are the annular members 42, 43, 42^A, 43^A which are 25 slidable over the face of the plate 18. The members 42, 43, 42^A, 43^A are distanced from each other by the right and left threaded 30 screw members 44, 44. Abuttable upon and slidable over the members 42, 43, 42^A, 43^A 35 are the outwardly extended annular members 45, 46, 45^A, 46^A, which are distanced from each other by the right and left threaded screw members 47, 47. Abuttable upon and slidable over the members 45, 46, 45^A, 46^A 40 are the outwardly extended annular members 48, 49, 48^A, 49^A, which are distanced from each other by the right and left threaded screw members 130, 130. These series of 45 annular members are stepped in order to fit closely one over the other as shown in Fig. 5, and are held upon the foraminous plate 18 by means of the annular members 131, 131.

The foraminous plate 17 comprises a series of openings connected with the series of tubular members 50, 50, 50^A, 50^A, said tubular members extending from the plate 17 outwardly to the members 19, 19^A.

Within the conical members 19 and 19^A are divergent cones 30, 30^A, supported by the members 31, 31, 31^A, 31^A.

In order that the cloth 25 may be wound 50 evenly upon the reel, the following device is employed: The two supports 70, 70^A are connected by the bars 71, 71. The upper portion 72 of each of the supports 70, 70^A has a vertical opening or slot 73. A heavy roller 74 has the shaft 75 capable of being carried 55 by the support 72 and revoluble therein. A means, as the hoisting hook 76 is capable of removing the roller 74 and the shaft 75 from the slit 73.

60 A chain cover 80 suitable for encompassing the rolled cloth 25 is comprised as follows: A series of links 81, 81, having downwardly extended serrated members 82, 82 are connected together by the links 83, 83, in 65 such a manner that the links of the chain

cover 80, may be folded over to reduce either the length or width of the cover, and any suitable clamp may be employed to maintain the chain cover in close position around the cloth 25.

70 A valve 90 allows the liquor to be drained from the dyeing chamber.

A testing device 151, capable of containing a sample of the fabric, is connected by the pipe 132 and the opening 133, passing 75 through the slidable members, with the chamber 110.

Two perforated steam pipes 134, 134^A are introduced into the dyeing chamber.

In the modification shown in Fig. 8, the 80 tubular members 50, 50^A are replaced by a series of tubular members 120, 120, 120^A, 120^A which extend from the inner face of the foraminous plate 17 outwardly into the members 19, 19^A, the walls 121, 121^A of the 85 tubular members converging upon and being abuttable upon the inner faces of the cone members 30, 30^A.

In the modification shown in Figs. 9 and 10, the parallel bars 111, 111 of the foraminous plate 18 are replaced by a series of parallel spaced rings 100, 100, supported by the members 101, 101.

In the modification shown in Figs. 11 and 12, the parallel bars 111, 111 of the foraminous plate 18 are replaced by a series of parallel spaced bars 102, 102 supported by the members 103, 103.

The operation of the device is as follows: The top 8 of the device is raised into the 100 position 8^A of Fig. 3, and the cloth 25 attached to the reel upon the foraminous plate 18.

The roller 74 is then placed upon the cloth and the device revolved, thus winding 105 the cloth upon the reel, the roller 74 maintaining the cloth in a smooth condition. When the cloth is wound, the roller 74 is raised into the position 74^B by means of the hooks 76, 76. By turning the right and left threaded screw members 44, 47, 130, 44^A, 47^A, 130^A, the slidable members 42, 45, 48, 42^A, 45^A, 48^A, are brought into abutting contact with the members 40, 40^A, and the members 43, 46, 49, 43^A, 46^A, 49^A, or as many as required for the thickness of the fabric roll, are brought into position against the sides of the fabric, these slidable members and the members 131, 131 closing all of the openings in the foraminous plate 18 except those immediately under the fabric.

The pipes 28 and 28^A are now connected with a source of dye-liquor, water, steam or air, as desired, and the particular operation continued during the revolution of the 125 reel.

The reactive agent passes through the pipes 28, 28^A, around the cones 30, 30^A of the conical members 19, 19^A, the tubes 50, 50^A, the foraminous plate 17, the chamber 110, 130

- the foraminous plate 18, the fabric 25 and the chain cover 80 into the receptacle, from which it flows through the pipe 10 for continuous circulation if desired.
- 5 I do not limit myself to the particular size, shape, number or arrangement of parts as shown and described, all of which may be varied without going beyond the scope of my invention as described and claimed.
- 10 What is claimed is:
1. In a fiber treating machine, in combination, a foraminous cylinder capable of having a fabric wound thereon, an outwardly extended flange fixedly attached to each end of the cylinder, a plurality of series of annular members slidable upon said cylinder, means whereby the annular members of a series may be separated at any predetermined distance from each other to about 20 upon the flange and a fabric wound upon the cylinder closing the openings in the cylinder between the flange and the fabric and means for forcing liquids, steam and air through the unclosed openings in the cylinder.
  - 25 2. In a fiber treating machine, in combination, a foraminous cylinder capable of having a fabric wound thereon, an outwardly extended flange fixedly attached to each end of the cylinder, a plurality of series of annular members, means whereby the annular members of a series may be separated at any predetermined distance from each other to abut upon the flange and a fabric wound upon the cylinder closing the 35 openings in the cylinder between the flange and the fabric, and means for forcing liquids, steam and air through the openings in the cylinder and through the fabric rolled thereon.
  - 40 3. In a fiber treating machine, in combination, a foraminous cylinder capable of having a fabric wound thereon, an outwardly extended flange fixedly attached to each end of the cylinder, a plurality of series of annular members slidable over said cylinder, means whereby the annular members of a series may be separated at any predetermined distance from each other to abut upon the flange and a fabric wound upon the 45 cylinder closing the openings in the cylinder between the flange and the fabric, means for revolving the cylinder and means for passing liquids, steam and air through the unclosed openings of the cylinder and through 50 the fabric.
  - 55 4. In a fiber treating machine, in combination, a foraminous cylinder capable of having a fabric wound thereon, an outwardly extended flange fixedly attached to each end of the cylinder, a plurality of series of annular members slidable over said cylinder, means whereby the annular members of a series may be separated at any predetermined distance from each other to abut upon the flange and a fabric wound upon the 60 cylinder closing the openings in the cylinder between the flange and the fabric, means for 65
- cylinder closing the openings in the cylinder between the flange and the fabric, a flexible foraminous covering capable of being adjusted to closely cover the fabric when wound upon the cylinder and means for 70 forcing liquids, steam and air through the openings in the cylinder within the wound fabric, the fabric and the cover.
5. In a fiber treating machine, in combination, a receptacle, an outer foraminous cylinder within the receptacle capable of having a fabric wound thereon, a second foraminous cylinder spaced within the first cylinder, outwardly extended flanges at each end of the cylinders, a plurality of series of 80 annular members slidable over the outer face of the outer cylinder, means for separating the members of each series to abut upon the edge of a fabric rolled upon the outer cylinder closing all the openings in 85 the outer cylinder except those around which the fabric is wound, means for maintaining the members in abutment against the fabric, means for revolving the cylinders and means for passing liquids, steam and air through 90 the cylinders and the fabric during their revolution.
6. In a fiber treating machine, in combination, a receptacle, an outer foraminous cylinder within the receptacle capable of having 95 a fabric wound thereon, a second foraminous cylinder spaced within the first cylinder, outwardly extended flanges at each end of the cylinders, a plurality of series of annular members slidable over the outer face of 100 the outer cylinder, means for separating the members of each series to abut upon the edge of a fabric rolled upon the outer cylinder closing all the openings in the outer cylinder except those around which the fabric is 105 wound, means for maintaining the members in abutment against the fabric, means for revolving the cylinders, tubular members connecting the openings in the inner cylinder to a supply source of liquids, steam and air, a flexible foraminous covering capable 110 of being adjusted to closely cover the wound fabric, and means for forcing liquids, steam and air outwardly through the device and the fabric wound upon the outer cylinder.
7. In a fiber treating machine, in combination, a receptacle, an outer foraminous cylinder within the receptacle capable of having a fabric wound thereon, a second foraminous cylinder spaced within the first cylinder, outwardly extended flanges at each end of the cylinders, a plurality of series of annular members slidable over the outer face of the outer cylinder, means for separating the members of each series to abut upon the edge 120 of a fabric rolled upon the outer cylinder closing all the openings in the outer cylinder except those around which the fabric is wound, means for maintaining the members in abutment against the fabric, means for re- 125
- 65 130

volving the cylinders and means for forcing liquids, steam and air through the device and the fabric carried thereby.

8. In a fiber treating machine, in combination, a foraminous cylinder comprising a series of spaced parallel members capable of having a fabric wound thereon, an outwardly extended flange fixedly attached to each end of said cylinder, a series of annular members slidable over said cylinder oppositely to each other and capable of closing a portion of the openings in the cylinder and means for maintaining the members in any predetermined position over the cylinder.

9. In a fiber treating machine, in combination, a receptacle, an outer foraminous cylinder comprising a series of spaced parallel members having outwardly extended projections within the receptacle, an inner foraminous cylinder spaced from the outer cylinder, tubular members connecting the openings in the inner cylinder with a supply source of liquids, steam and air, a series of slidable members over the outer face of the outer cylinder, slidably movable from each other to abut upon a fabric wound upon the cylinder closing all of the openings in the cylinder except those covered by the fabric, a flexible foraminous covering capable of close engagement with the exterior surface of the wound fabric, means for revolving the cylinders and the fabric and means for forcing liquids, steam and air through the device and the fabric during the revolution.

10. In a fiber treating machine, in combination, a receptacle, an outer foraminous cylinder within the receptacle capable of having a fabric wound thereon, a second foraminous cylinder spaced within the first cylinder, outwardly extended flanges at each end of the cylinders, a plurality of series of annular members slidable over the outer face of the outer cylinder, means for separating the members of each series to abut upon the edge of a fabric rolled upon the outer cylinder closing all the openings in the outer cylinder except those around which the fabric is wound, means for maintaining the members in abutment against the fabric, a testing device capable of containing fiber and connected with the space between the two foraminous cylinders, means for re-

volving the cylinders and means for passing liquids, steam and air through the cylinders and the fabric during their revolution.

11. In a fiber treating machine, in combination, a receptacle, an outer foraminous cylinder within the receptacle capable of having a fabric wound thereon, a second foraminous cylinder spaced within the first cylinder, outwardly extended flanges at each end of the cylinders, a plurality of series of annular members slidable over the outer face of the outer cylinder, means for separating the members of each series to abut upon the edge of a fabric rolled upon the outer cylinder closing all the openings in the outer cylinder except those around which the fabric is wound, means for maintaining the members in abutment against the fabric, a testing device capable of containing fiber revoluble with the cylinders and connected with the space between the two foraminous cylinders, means for revolving the cylinders and means for forcing liquids, steam and air through the device and the fabric carried thereby.

12. In a fiber treating machine, in combination, a receptacle, an outer foraminous cylinder comprising a series of spaced parallel members having outwardly extended projections within the receptacle, an inner foraminous cylinder spaced from the outer cylinder, tubular members connecting the openings in the inner cylinder with a supply source of liquids, steam and air, a series of slidable members over the outer face of the outer cylinder, slidably movable from each other to abut upon a fabric wound upon the cylinder closing all of the openings in the cylinder except those covered by the fabric, a flexible foraminous covering capable of close engagement with the exterior surface of the wound fabric, a testing device capable of containing fiber revoluble with the cylinders and connected with the space between the two foraminous cylinders, means for revolving the cylinders and the fabric and means for forcing liquids, steam and air through the device and the fabric during the revolution.

Signed at Philadelphia, in the county of Philadelphia and State of Pennsylvania this 18th day of June, 1917.

HOWARD M. DUDLEY.
